UNITED STATES PATENT OFFICE.

FREDERICK W. STUKENBORG, OF CHICAGO, ILLINOIS.

ART OF AND DEVICE FOR PICKING COTTON.

1,402,724.

Specification of Letters Patent.

Patented Jan. 3, 1922.

Application filed December 27, 1920. Serial No. 433,439.

To all whom it may concern:

Be it known that I, FREDERICK W. STUKENBORG, a citizen of the United States, and a resident of Chicago, in the county of Cook 5 and State of Illinois, have invented certain new and useful Improvements in the Art of and Devices for Picking Cotton; and I do hereby declare that the following is a full 10 clear, and exact description thereof, reference being had to the accompanying drawings, and to the characters of reference marked thereon, which form a part of this specification.

This invention relates to improvements in 15 the art of picking cotton, and refers to a novel method of and device for picking cotton by the use of rotative brush elements, to serve as the active factor to rapidly remove the cotton from the bur and to release 20 it from the brush elements and preferably into the influence of a medium which is active to continuously remove the cotton away from the brush elements to a suitable place of disposal of the cotton.

25 In accordance with my novel method of picking cotton, it is proposed to withdraw the cotton from the bur by applying thereto rapidly rotating picker element or elements having peripheral, outstanding pliable, resili- 30 ent fibre penetrating media of a character to permit the cotton to adhere thereto, and of a pliability which will cause them to adapt themselves to finding their way into the cells of the bur to become enmeshed with the 35 cotton, and of a resiliency such as will quickly straighten themselves to their initial positions to draw or pull the cotton away from the bur backwardly past or between the rotative element or elements thus 40 characterized, and to rotate the picker element or elements at a peripheral speed that will generate a sufficient centrifugal force to release or throw the seed cotton directly in a rearwardly moving current of conveying 45 air.

The speed or conveying activity of the air is such, when air is employed to convey the cotton, as to carry rearwardly the cotton released from the picker element or elements 50 in such manner as to avoid any or substantial reengagement of the cotton with the picker element or elements so as to thereby prevent clogging of the picker element or elements in a way to impede proper picking 55 and doffing functions thereof. If the cotton laden moving column of air strikes a screen

or other cleaner in its path, dirt and other foreign substance in the loosened cotton, opened by the action of the brushes, will be projected through the screen or cleaner, and 60 the clean cotton will fall into a suitably placed receptacle to receive the same. The air to produce the moving column can be admitted in part through the mouth of the casing and in part at the rear of the picker 65 element or elements, and in any event so that the conveying air will be active to receive and convey the cotton rearwardly from the picker element or elements.

The action of the high speed picker ele- 70 ment or elements, by rapidly drawing and combing the cotton from the bur, with the bristles penetrating the cotton and by their resiliency movable therein while the cotton is passing the picker element or elements, 75 and by centrifugally releasing the cotton from said picker element or elements, produces a fluffy seed cotton for efficient separation of boll dirt and moisture therefrom, and also conditions the cotton for good 80 ginning.

The doffing or releasing force of the picker element or elements is controlled by means which hold the cotton engaged therewith until a predetermined doffing zone at the 85 rear of the picker element or elements is reached, whereby the release of the cotton in the conveying air is assured. Such doffing or releasing force thus produced and controlled may be sufficiently active, in itself, 90 to throw the cotton through space away from the picker element or elements without the use of a current of conveying air, in the event the area into which the cotton is thus thrown is arranged to permit the cotton to 95 fall away therefrom.

A device or apparatus embodying my invention, and by which my novel method of picking cotton can be practiced, may embrace, in combination with a brush or 100 brushes, a casing to enclose and furnish bearings therefor. The casing has an open mouth at which the brush or brushes are mounted in a way to draw the cotton backwardly past or between them, the head or 105 casing being connected with means, as an exhaust fan, to produce a rearward flow of air to carry the cotton rearwardly away from the brush or brushes to a suitable place for disposal of the cotton. The brush or 110 brushes are operatively connected with driving power to give speed of rotation thereto

- 2
- to generate sufficient centrifugal force to release or project the cotton rearwardly therefrom in the rearwardly moving air, and thus to doff the cotton from the brush 5 or brushes. One or more than two brushes can be employed, preference being had to two or more to take advantage of the grasping effect of the bight between interacting brushes.
- 10 Reference to "bristles" when herein specifically used is to be taken as any suitable form of bristle-like media, of either animal, vegetable or other origin, which have properties of pliability to bend against a resistance, so as to be capable of wiping over hard surfaces, as that of a cotton bur, and to find their way into the bur formation for contact with the cotton fibre, a resiliency to quickly restore themselves when unrestrained, while at the same time sufficiently delicate in their action on the cotton fibre to avoid breaking or otherwise damaging it, and also possessing a property to adapt themselves to the natural twist or spirality 20 peculiar to cotton, that give spinning quality to the cotton fibre, to enmesh with the fibre in a way to give effective pull of the bristle media on the fibre to draw the cotton away from the bur.
- 25 Hog bristles possess these characteristics to a high degree and are recommended because they are peripherally formed to enmesh with the cotton fibre to draw them from the bur. It is known that the natural spirality or twist of the cotton fibre that gives it spinning qualities is such that an entire lock tends to follow a single or a number of fibres or strands adhered to a moving medium having the general characteristics 30 of such bristles. Difficulty has been experienced, however, in releasing the cotton fibre from bristles of this character by reason of the same characteristics that give value to the picking qualities thereof.
- 35 I have discovered that the weight of the seed in seed cotton is a potential factor, not heretofore recognized, in thus clearing brushes that are operated at high peripheral speed to give the seed cotton thrown backwardly 40 by the brushes the required momentum to effectively clear the cotton from the brushes. The proportionate weight of seed to the fibre or staple in average cotton is substantially two-thirds seed and one-third fibre, and the 45 momentum of this substantial weight of the seed in seed cotton becomes an active factor, when thrown rearwardly by centrifugal force generated by the rapidly rotating brushes, to project it sufficiently far from 50 the brushes to prevent reengagement of the cotton with the brushes.
- 55 The peripheral speed of the brushes depends somewhat on the condition of the cotton with respect to its stage of maturity, 60 its condition of moisture, length of staple,

and the like. A machine to be universal should be operated with a brush speed that will efficiently pick the usual and all conditions of cotton. I have found in practice that the speed of brush rotation need not 70 vary for effective work on different conditions of cotton but a few hundred rotations per minute and that an average speed of twelve to eighteen hundred rotations per minute produces good results. This is not 75 to be taken, however, as a limitation of the operative speed of brush rotation; the peripheral speed of the brushes being maintained when picking all conditions of seed cotton sufficient to release or doff the cotton therefrom by centrifugal action. The speed of air flow can be maintained at a rate to correspond with the rate of speed that the cotton is projected into the moving column of air.

80 With the construction herein disclosed, the brushes can be connected to the driving mechanism therefor in a simple way, which driving mechanism may be a suitable shaft connected to a motor back of the head, or 85 may be by a direct connection to an electric, air, or other motor.

85 In a picking mechanism embodying my invention, the head or casing which partly surrounds the brushes and supports the bearings therefor, and through which a moving column of air can be induced and properly directed will desirably be provided in rear of the mouth with inlet openings, so that a portion of the air passed through the head 90 or casing will enter the same through said openings. A portion of the air, however, can enter through the mouth at the front of the head or casing, especially when the brushes are, so to speak, empty or are not pulling the 95 cotton rearwardly past or between the same. When substantially large slugs of seed cotton are passing backwardly past or between the brush or brushes, the flow of air is, to a 100 substantial extent, throttled at the mouth of the head or casing, and at this time air can enter the head or casing through all of the 105 available inlets that will afford the desired volume and activity of the rearwardly moving air column.

110 I have shown in the drawings two forms of construction embodying my invention, and for practicing my novel method, and in said drawing have shown brushes to be operated by a simple connection to a motor which, as 115 shown, is supported on the head. Such motor, however, may be otherwise supported closely adjacent to the head, or the brushes may be rotated from other suitable source of power that will give the required speed of 120 rotation to the brushes.

125 As shown in said drawings:

Figure 1 is a partial side elevation and partial section of a picker mechanism embodying my invention.

Figure 2 is a section in a plane at right angles to the plane of Figure 1.

Figure 3 is a side elevation of the mechanism looking toward the side opposite that shown in Figure 2.

Figure 4 is an end view of the mechanism.

Figure 5 is a perspective view, showing a modification.

Figure 6 is a diagrammatic view, showing 10 a connected picker head and suction fan for giving movement to the column of air and showing also a means for separating dirt from the seed cotton.

As shown in the drawings, 10 designates, 15 as a whole, the head or casing of the picker mechanism which, as herein shown, is made of two like parts 11, 11, joined at their edges by bolts 12, 12, extending through overlapping lugs 13, 13 at said margins. The head 20 is enlarged at its front end and is there open to provide an intake mouth 14 through which the cotton passes into the head.

15, 15 (Figures 1, 2, and 4) designate two interacting picker brushes, of which there 25 can be more than two, which are mounted in the head and are adapted to rotate in the direction indicated by the arrows on Figure 2 on axes parallel to each other. Said brushes comprise cores 16, 16 and tufts of bristles 30 17, 17 that are fastened in the core and extend radially therefrom. The brush cores 16 can be encased by metal sleeves 18, 18, which, when employed, may extend a distance beyond the ends of the cores 16, to constitute overlapping shell-like enclosures for 35 the bearings 19 of the brush core shafts 20 that are supported on opposite walls of the casing or head.

Said shafts extend at one side of the head 40 or casing beyond the adjacent side wall and are provided with gears 23, 23, through which power to drive the brushes is transmitted. As herein shown said gears 23 are spiral gears, and they mesh at their proximate sides with a spiral pinion 24 that is 45 fixed to and rotates with the drive shaft 25 of an electric or other motor 26. The outer end of said shaft 25 is mounted in a bearing 25' fixed to the adjacent casing or head wall. 50 Said motor can be attached to and carried by the head or casing or can be otherwise supported. When supported on the casing or head wall, the motor can be enclosed by the same dust guard 27 (Figure 4) that also 55 encloses the gears 23 and 24.

The body 28 of the head or casing is made short and is connected at its rear end to a flexible or other tube 29, which is adapted to lead backwardly to an exhaust fan 30 or 60 other suitable source for creating a backward air flow. The casing is formed to provide in rear of the brushes an unobstructed chamber in which the cotton is released and said casing terminates in rear of said cham-

ber in a reduced part or neck for connection 65 with the conveyor tube 29. The fan can discharge the cotton and air through the outlet 31 against a suitable cleaner, as the screen 32, shown in Figure 6, a receptacle 33 being suitably located to receive the picked and 70 clean seed cotton.

In rear of the mouth 14 the head or casing will be provided with an air inlet opening, or openings, 34 of ample area to serve as inlets to furnish a desired volume of air for 75 the rearwardly moving column of air in the head and in the tube. As herein shown, there are a number of such openings 34 which are located adjacent to the rear sides of the brushes and in such relation to the rearmost 80 sides of the brushes as to always insure movement of air at the zone where the cotton is doffed from the brushes by force generated by the centrifugal action of the brushes.

In order to avoid throwing an overload 85 on the motor, or the driving connections from a driving motor for the brushes, a slip clutch 36 may be interposed in the driving connection.

When guards 37 are employed (Figures 90 1, 2, and 4), they can be made of wire of proper gauge and arranged in sets to extend from opposite walls towards, but terminate short of, each other across the front of the brushes and within the mouth 14. 95 They may be fastened to anchor bars 38 fixed to the outer sides of the walls which support said guards.

The high speed of the brushes serves to 100 rapidly pick or pull the cotton away from the bur and draw it backwardly between and project it rearwardly from the brushes. This rapidity of removing the cotton from the bur, combined with the arrangement whereby the rearwardly moving conveying 105 air is at all times maintained active gives effect to the method and apparatus to produce high efficiency and capacity in picking cotton.

Another advantage of the construction 110 referred to is that the head and mechanism at the head can be materially reduced in weight, and the head may be materially shortened. The shortening of the head enables the flexible tube, through which the 115 cotton is conveyed away from the head, to be brought closely to the brushes for junction with the head. This permits of a larger flexibility of direction of the head to the boll when picking from the plant, thus 120 making the work of directing the head less laborious and more rapid and accurate.

In Figure 5 is shown a form of a cotton picker in which but a single brush element 15 is employed at the mouth 14 of the casing 125 10. Said brush is located at one side of the center of the mouth and coacts with a lip 41 that extends forwardly from one side

of the casing and beyond the mouth, whereby the cotton is drawn into the head between the bristles of the brush and said lip.

In the construction shown in Figures 1 to 4, inclusive, each brush opposes and coacts with the other to hold the cotton on the brushes from the position, at the front thereof, at which they engage the cotton at the bur, to the position at the rear thereof of where the brush peripheries move away from each other. This latter position establishes the doffing zone. In the construction shown in Figure 5 the brush is opposed by a side wall of the casing to thus control the casting off action and to establish a predetermined doffing zone. This control, in connection with the centrifugal force, is important regardless of the particular character of picker element employed.

20 I claim as my invention:

1. The method of picking cotton from the boll by the use of rotative picker means having outstanding pliable, resilient bristles, which comprises the steps of inducing a rearward flow of conveying air backwardly from the picker means, rotating the picker means in contact with the cotton boll to withdraw the cotton therefrom, and at a peripheral speed which generates sufficient centrifugal force to doff the cotton from the picker means and controlling the doffing force to direct the cotton into the conveying air.

2. The method of picking cotton from the boll by the use of coacting, opposed rotative brushes, which comprises the steps of rotating the brushes to draw the cotton rearwardly therebetween, and at a speed to generate sufficient centrifugal force to doff the seed cotton freely therefrom, and inducing a rearward flow of conveying air away from said brushes to receive the cotton doffed from the brushes and at a velocity to prevent reengagement of the doffed cotton with the brushes in a manner to clog the brushes.

3. The method of picking seed cotton by rotative picker elements having outstanding coacting pliable, resilient bristles, which consists in the steps of inducing a rearward flow of air away from said elements, and rotating the picker elements at a peripheral speed to pick the cotton and to generate sufficient centrifugal force to doff the seed cotton from the picker elements into said moving column of air, and whereby the coacting bristles and the centrifugal force of the high speed picker elements act to stretch and open the cotton locks to produce a fluffy seed cotton.

60 4. The method of picking seed cotton by the use of rotary brush means, which comprises the steps of presenting the brush means to the cotton to be picked, rotating said brush means to pick and draw the cotton rearwardly, and at a sufficient periph-

eral speed to doff the seed cotton from the brush means by momentum of the seed cotton derived from the action of centrifugal force on the seed cotton mass.

5. The method of picking seed cotton by 70 the use of rotary brush means, which comprises the steps of presenting the brush means to the cotton to draw the cotton rearwardly, rotating said brush means at high peripheral speed to pick the cotton and to 75 generate sufficient centrifugal force to doff the cotton from the brush means, and controlling the release of the cotton from the brush means to establish a predetermined doffing zone of the cotton from the brush 80 means.

6. A cotton picker for seed cotton comprising a casing having a cotton receiving mouth, rotating brush means thereat comprising outstanding, pliable, resilient bristles, 85 means to induce a rearward flow of air backwardly from said brush means, and means to rotate the brush means at a peripheral speed to generate sufficient centrifugal force to doff the cotton from the bristles, together 90 with means arranged to assist the picking and to control said doffing force to release the cotton in the rearwardly moving air.

7. A cotton picker for seed cotton comprising a casing having an intake mouth, 95 opposed, coacting picker brushes thereat, means to induce a rearwardly flowing column of air backwardly from said brushes, and means to rotate the said brushes towards each other at their forward sides and at a peripheral speed to generate sufficient centrifugal force to cause the cotton to be thrown from the brushes directly in the rearwardly moving column of air.

8. A cotton picker for seed cotton comprising opposing, coacting oppositely rotative picker brushes to draw the cotton rearwardly between them, and means to rotate said brushes towards each other at their forward sides and at a speed to generate sufficient centrifugal force to doff the cotton therefrom.

9. A cotton picker for seed cotton comprising a casing having a cotton receiving mouth, opposed, coacting rotative brushes thereat, said casing having an unobstructed chamber in the rear of the brushes, and adapted for connection in rear of said chamber with a conveyor tube, means to induce a rearward flow of air away from said brushes through said tube, and means to rotate said brushes towards each other at their forward sides and at a peripheral speed to generate centrifugal force to release the cotton from said brushes in said rearwardly flowing air.

10. A cotton picker for seed cotton comprising a casing having a cotton receiving mouth, rotating brush means thereat, comprising outstanding, pliable, resilient bristles, means to induce a flow of conveying air 130

through the casing and backwardly from the brush means, and means to rotate the brush means at a peripheral speed to generate sufficient centrifugal force to doff the seed cotton from the bristles, together with means arranged to assist the picking and to control said doffing force to release the cotton in the rearwardly moving air, said casing being provided at the zone of separation of the cotton from the brush means with air inlet or inlets.

11. A cotton picker for seed cotton comprising a casing and cooperative rotative picker brush means to draw the cotton rearwardly past the same, means to rotate said brush means at a speed to generate sufficient centrifugal force to doff the cotton therefrom, and means to control the release of the cotton from the brush means to establish a predetermined doffing zone at the rear of said brush means.

12. A cotton picker for seed cotton comprising a casing and cooperative rotative picker brush means to draw the cotton rearwardly, means to rotate the brush means at a peripheral speed to generate sufficient centrifugal force to release the cotton therefrom, means to induce a rearward flow of conveying air from the brush means, and means to control said releasing force to release the cotton from the brush means to direct it in said conveying air.

13. A cotton picker for seed cotton having a manually directed head comprising a casing and cooperative, opposing, coacting oppositely rotative picker brushes, and means to rotate said brushes toward each other at their forward sides to draw the cotton rearwardly between them, and at a speed to generate sufficient centrifugal force to freely release the cotton therefrom. 35 40

14. A cotton picker for seed cotton having a manually directed head comprising a casing and cooperative, opposing, coacting oppositely rotative picker brushes, means to rotate said brushes toward each other at their forward sides to draw the cotton rearwardly between them, and at a speed to generate sufficient centrifugal force to freely release the cotton therefrom, said casing being provided in rear of said brushes with means to admit air thereto, and means to induce a current of conveying air rearwardly from said brushes to receive and convey rearwardly the released cotton, and at a velocity to avoid reengagement of the released cotton with the brushes. 45 50 55

In witness whereof I claim the foregoing as my invention, I hereunto append my signature this twenty-first day of December, 60 1920.

FREDERICK W. STUKENBORG.
